FIRE ESCAPE.

No. 327,976.

Patented Oct. 6, 1885

UNITED STATES PATENT OFFICE.

THEODORE B. WOODWARD, OF NORWAY, PENNSYLVANIA.

FIRE-ESCAPE.

SPECIFICATION forming part of Letters Patent No. 327,976, dated October 6, 1885.

Application filed March 20, 1885. Serial No. 159,560. (No model.)

To all whom it may concern:

Be it known that I, THEODORE B. WOODWARD, a citizen of the United States, residing at Norway, in the county of Chester and State of Pennsylvania, have invented certain new and useful Improvements in Fire-Escapes, of which the following is a description.

This invention relates to that class of fire-escapes by means of which either people or merchandise may be lowered from the windows of a burning house; and its object is to provide means whereby the walls of an escape-car may be adjusted to admit passengers and then set to shield them from flames which 15 may shoot out of lower windows; means whereby the car may be hung upon a house to descend in front of the windows thereof, and means whereby the car may be raised, and whereby its descent may be controlled either 20 by the occupants thereof, by persons on the ground, or by persons on any floor of the house.

To this end my invention consists in the construction and combination of parts forming 25 a fire-escape, hereinafter described and claimed, reference being had to the accompanying drawings, in which—

Figure 1 is a front elevation of a portion of a house showing my fire-escape thereon. Fig. 30 2 is a transverse vertical section of a portion of a building, showing the same invention in side elevation. Fig. 3 is an enlarged view of the escape-car in transverse vertical section.

35 A represents the house, which may be of any number of stories, of any style of construction, and suited to any purpose.

B represents the body of the escape-car, which I prefer to make of incombustible material—such as sheet-iron. I have shown it 40 shaped as a chair convenient for one or more persons to sit in while descending from a house.

C is a bail, which may be wire rope or a 45 chain secured to the car, and provided with a ring, D, where the hooks of two lifting-chains, E, may be attached or detached at will, so that the car when not in use may be removed and kept in any convenient place.

50 F is a roller journaled in brackets G, located above the window of an upper story within the house.

H represents two pulleys over which the chains E pass into the house to be wound on the roller F.

55

I represents one or more chains mounted in grooves on the ends of the roller F, and passing down through the various stories of the house around pulleys h, to serve as continuous belts, whereby persons on any floor may 60 raise or lower the car by turning the roller.

J is a brake pivoted to the house to lie upon the roller, and K is a chain extending therefrom down through each story of the house, whereby persons on any floor may 65 control the descent of the car by applying the brake upon the roller.

L is a short chain attached to the car by means of a fixed hook, M.

N is a hook secured on the window-sill of 70 each story of the house in the vertical line of the escape, upon which the chain L may be temporarily secured to hold the car while the latter is being filled. The hook N is pivoted to revolve, so that when the car is ready to 75 descend the hook is to be turned with its point out of the window, when it will allow the chain L to pull off, leaving the car free to be controlled by the chains I and K by persons in the house.

80

O is another chain attached to the brake and extending into the car, where it is to be hooked to another chain, P, which is kept wound upon a winch, Q, beneath the seat of the car. By this means a person in the car may control the 85 brake to govern his own descent with the car, the chain P paying off from the winch Q as the car descends. When once down, the chain P may be unhooked from the winch and left to hang to the ground, whereby persons on the 90 ground may control the descent of the car by the brake.

R is a winch upon which a chain, S, may be wound when not in use. When needed, this chain is to be run off from the winch, to be 95 used by persons on the ground in guiding the direction of the descent of the car, so that it may escape window-cornices, or so that the occupants may be landed at some distance from the house.

100

T is a wire hung to the house above the window, and made long enough to reach the car when hung to the window-sill. U is a wire or wire rope to be attached at one end to a

staple or hook, V, fixed at some convenient point away from the house, to be paid out from the car through its bottom as it ascends the first time, and to be attached at its upper end 5 to the wire T. The wire U may also pass through the ring D to guide the car in line. The wires T and U form a sort of rail on which the car may slide up and down. When this rail is used, the guide-chain S may be idle; and 10 yet it is not safe to dispense with chain S, because the wind may blow the flames in a direction to prevent the use of the rails T U.

a represents a movable shield fitted around the walls of the car, to be raised above the said 15 walls to guard the passengers from flames and smoke.

b is a wire cord by which the shield may be raised or lowered. c c are guides attached to the sides of the car to retain the shield in 20 place, permitting it to rise and fall. d is a shield for the back of the car, fitted to slide therein, descending by gravity, and being raised by a yoke, e, which depends from the shield a when the shield is raised. Both shields 25 are to be lowered to permit passengers to enter the car freely at its back. They may leave it from the front when safe on the ground. f represents one or more chains to be wound on the roller F, and to extend to the ground, 30 whereby persons outside may wind up the roller to raise the car.

What I claim as my invention, and desire to secure by Letters Patent, is—

1. The combination, in a fire-escape, of a 35 roller, F, journaled in brackets above a window within a house, the pulleys H, journaled above the window on its outside, the car B, provided with the bail C and ring D, the chains E, attachable at one end to the ring D, extending 40 over the pulleys H, and attached at the other end, to be wound upon the roller F, the chains I, mounted on the roller and extending down through the different stories of the house, the pulleys h therefor, the brake J, pivoted to 45 the house, to lie upon the roller F, and the two chains K and O, extending therefrom,

one passing down through the house and the other out at the window, substantially as shown and described.

2. The combination of the roller F, journaled 50 in a house, the chains I, mounted on the roller as belts, the chains E, secured to wind thereon, the chains f, secured to wind upon the roller F in a direction opposite to the chains I, a car, B, securable to the chains E, a wire, T, hung 55 to the house above the window, the staple V, secured to the ground, and the wire U, adapted to be hooked to the staple at one end and to the wire T at the other end, and the ring D, attached to the car, the wire U, passing through 60 the car and the said ring as a rail therefor.

3. The combination of the car-body B, the guides c c, secured thereto, the shield a, fitted around two or more sides of the car to slide 65 up and down behind the guides c c, and the cord b, adapted to raise the shield, as shown and described.

4. The combination of the car-body B, the guides c c secured thereto, the shield a, fitted to slide within the guides, the cord b, adapted 70 to raise the shield, another shield, d, fitted to slide in the back of the car, and a yoke, e, depending from the shield a, to engage the shield d, substantially as shown and described.

5. The combination of the car B, the roller 75 F, journaled in a house, the chains E, connecting the car with the roller, the chain L, secured at one end to the car and having a loop at the other end, and the hook N, pivoted to revolve in the window-sill, substantially as described, 80 whereby the chain L may be attached, and whereby the same will be set free when the hook is turned with its point outward from the window.

The above specification of my invention 85 signed by me in the presence of two subscribing witnesses.

THEODORE B. WOODWARD.
